UNITED STATES PATENT OFFICE.

PETER JOHNSON, OF RENVILLE, MINNESOTA.

HORN-TIP FOR CATTLE.

SPECIFICATION forming part of Letters Patent No. 373,776, dated November 22, 1887.

Application filed May 18, 1887. Serial No. 238,632. (No model.)

To all whom it may concern:

Be it known that I, PETER JOHNSON, a citizen of the United States, residing at Renville, in the county of Renville and State of Minnesota, have invented certain new and useful Improvements in Horn-Tips for Cattle; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention is a device to be secured to the horns of vicious cattle to prevent them from goring others; and it consists in the novel construction and arrangement of its parts, as hereinafter described.

In the accompanying drawings, Figure 1 shows the device attached to the horns of a steer. Fig. 2 is a face view of one half of the device, the other half being exactly similar thereto. Fig. 3 is a sectional view of Fig. 2, cut on the line $x-x$. Fig. 4 is a perspective view of one of the nuts by means of which the device is secured on the ends of the animal's horns.

My invention is described as follows: I make two plates, a b , each having in one end a perforation, a' , and a slot, b' , and hinged to the other end a threaded nut, c . The said nuts c are hinged to the said plates by passing the ends c' of said plates through the opening c^2 in said nuts c and over and around the hinge-bar c^3 , or by any equivalent means, the ends of the said plates being first cut down and made narrow enough to pass through said openings c^2 . The two plates are joined together by

passing a bolt, d , through the perforation a' in the plate a , thence through the slot b' in plate b , and another bolt, d' , through the slot b' of the plate a and through the hole a' of the plate b . The arrangement of the said holes and slots in connection with the said bolts enables me to make the device longer or shorter, and thus adapted to be fitted on the horns of different animals, though they may not be the same distance apart.

The device is applied as follows: I take one half of the device—say plate b —and screw its nut c on the end of one horn until it is perfectly tight. Then I take the other plate, a , and screw its nut on the end of the other horn until it is perfectly tight. Then I saw the ends of the horns off even with the upper faces of the said nuts. Then I turn the plates up over the nuts and bring them together in the center and pass the pins d d' through, as above described, and secure them by nuts.

Having thus described my invention, what I claim as new, and desire to secure by Letters Patent, is—

The combination of the plates a b , having in one end the perforations a' and slots b' , threaded nuts c , having in one end the opening c^2 and the hinge-bar c^3 , said nuts being hinged to the ends of said plates, and bolts d d' , passing through said perforations a' and slots b' , and secured in place by nuts, substantially as shown and described, and for the purpose set forth.

In testimony whereof I affix my signature in presence of two witnesses.

PETER JOHNSON.
